No. 791,848.

PATENTED JUNE 6, 1905.

J. E. WILSON.

RULE.

APPLICATION FILED JULY 9, 1904.

UNITED STATES PATENT OFFICE.

JOHN ELWOOD WILSON, OF LANCASTER, PENNSYLVANIA, ASSIGNOR
OF ONE-HALF TO ADOLPH J. E. KOPCKE, OF LANCASTER, PENN-
SYLVANIA.

RULE.

SPECIFICATION forming part of Letters Patent No. 791,848, dated June 6, 1905.

Application filed July 9, 1904. Serial No. 215,855.

To all whom it may concern:

Be it known that I, JOHN ELWOOD WILSON, a citizen of the United States, and a resident of Lancaster, in the county of Lancaster and State of Pennsylvania, have invented a new and Improved Rule, of which the following is a full, clear, and exact description.

My invention relates to a rule; and the objects thereof are to provide means for calculating distances and angles. The rule is capable of general use; but it is especially applicable for building purposes.

Reference is to be had to the accompanying drawings, forming a part of this specification, in which similar characters of reference indicate corresponding parts in all the figures.

Figure 1 is a plan view of a preferred form of my invention, showing the parts in operative position. Fig. 2 is a fragmentary view showing a portion of the device on a large scale. Fig. 3 is a sectional view on the line 3 3 of Fig. 2. Fig. 4 is a rear view of the parts or blades shown in Fig. 2; and Fig. 5 is a view of the entire device, showing it closed up.

In the drawings the rule is shown as composed of three parts *a b c*. These parts are preferably made exactly alike; but, if desired, modifications may be made in any of them without changing the others. They are preferably provided with circular enlargements at one end. The enlargements *b'* and *c'* of the parts *b* and *c* are shown in the drawings. The corresponding circular enlargement on the part *a* is not illustrated in the drawings. These circular enlargements are provided with centers exactly in line with the inner edge of each rule or the blade thereof and are provided with protractors *b²* *c²* concentric with the above-mentioned centers.

The two parts *a* and *b* are preferably connected together by means of a slide *d*, which is usually bent around the body of the part *a*, being provided with flanges *d'* for the purpose of holding it in position and permitting it to slide along the main blade *a*. The blade *b* is mounted upon this slide by means of a thumb-screw *e*, concentric with the protractor *b²* and so placed that its center will be coincident with the line passing along the inner edge of the blade *a*. The blades *a* and *c* are

connected together by a similar thumb-screw *e*, so that the two inner edges will meet at the pivotal point.

A mark *f* is formed upon the edge of the blade *a* for use in reading the protractor *c²*, so as to find the angle at which the blade *c* is set with respect to the blade *a*. In the same manner a notch or projection *g* is provided on the slide *d* for the purpose of reading the protractor *b²*. It will be observed that by putting the slide at the extreme end of the blade *a* the blades *b* and *c* may be folded together, as shown in Fig. 5, the blade *c* covering the blade *a*. Furthermore, it will also be obvious that the slide *d* may be set at any desired point upon the blade *a* and the other two blades extended in a line with the blade *a*, so that the device can be used as a measuring instrument for lengths up to the combined length of the three blades.

Although I have illustrated a particular embodiment of my invention, it will be obvious that the latter is not strictly limited thereto and that other forms may be used without departing from the spirit of the invention. More than three blades may be employed if the work demands it, and any sort of a scale may be employed on the blades. The one which I prefer to use, however, is that known as the "carpenter's" scale, in which the inches are divided in twelfths, so that for purposes of calculation they may be regarded as feet and conveniently represent the inches also. This rule can be used in all kinds of framing and for calculating the various parts of triangles of all kinds.

One manner of using the device will be obvious from Fig. 1. The blade *b* may be set at half the width of a building, and the blade *c* being placed at the desired pitch would give the cut and length of a rafter. In the same way lengths of rails and height of rise on stairways may be obtained by setting the blade *b* at the desired length of the stairs and setting the blade *c* so that it will intersect with the blade *b* at a point indicating the desired height. The pitch and length of rake may then be obtained and read directly from the device.

The device may also be used for other forms

of triangles and for figuring the lengths and cuts of braces for trusses and the like. It is to be understood, however, that the shorter edges or "inside" edges, as they have been called, 5 are the ones upon which the readings are to be taken, for the reason that the centers of the circular extensions are all in line with these edges. The blades may be reversed from the positions shown, if desired. The 10 blade *c*, for example, may be turned over to make the working edges come on the inside. Then all of the working edges would be together and form a complete triangle.

Having thus described my invention, I claim 15 as new and desire to secure by Letters Patent—

1. The combination of a main blade having a circular end scaled to constitute a protractor, a second scaled blade having a circular end, said blades being pivoted together at the 20 centers of said circular ends, and a third scaled blade having a circular end scaled to constitute a protractor movably and pivotally mounted on the first blade, the center of the last-named circular end being located on a 25 line coincident with the edge of the main blade, and each of said blades being of the same size and shape as, and interchangeable with, the others.

2. The combination of a main blade having 30 a circular end scaled to constitute a protractor, a second scaled blade having a circular end, said blades being pivoted together at the centers of said circular ends and each free to describe a complete circle about their pivot, 35 and a third scaled blade having a circular end scaled to constitute a protractor movably and pivotally mounted on the first blade and free to describe a complete circle about its pivot, the center of the last-named circular end being located on a line coincident with the edge of 40 the main blade, the circular ends of said blades being of the same size and each blade being interchangeable with the other.

3. The combination of a main blade having

a circular end scaled to constitute a protractor, 45 a second scaled blade having a circular end, said blades being pivoted together at the centers of said circular ends, and a third scaled blade having a circular end scaled to constitute a protractor movably and pivotally 50 mounted on the first blade, the center of the last-named circular end being located on a line coincident with the edge of the main blade and each of said blades being a counterpart of the others, said second and third 55 blades being movable on the main blade independently of each other and each blade being interchangeable with one of the others.

4. The combination of a main blade having a circular end scaled to constitute a protractor, a second scaled blade having a circular end, said blades being pivoted together at the 60 centers of said circular ends, a third scaled blade having a circular end scaled to constitute a protractor movably and pivotally 65 mounted on the first blade, the center of the last-named circular end being located on a line coincident with the edge of the main blade and each of said blades being a counterpart of the others, said second and third 70 blades being movable on the main blade independently of each other, a slide for connecting the third blade with the first one, said slide comprising a piece of sheet metal bent upon itself and adapted to inclose the main 75 blade, and a clamping device passing through both parts of said slide and engaging the third blade at the center of its circular end, said slide also being provided with a mark for registering with the protractor on said third 80 circular end.

In testimony whereof I have signed my name to this specification in the presence of two subscribing witnesses.

JOHN ELWOOD WILSON.
